END HOUSING ASSEMBLY FOR RAILROAD CAR DRAFT GEARS

Robert W. Gierlach, Chicago, Ill., assignor to Standard Car Truck Company, Chicago, Ill., a corporation of Illinois

Filed Aug. 4, 1964, Ser. No. 387,344
7 Claims. (Cl. 213—8)

This invention relates to railroad car draft rigging and has for one object to provide such a device which may be easily assembled, installed, serviced and maintained.

Another object is to provide a special type of sliding draft gear end housing which will without the necessity of special coupler shanks permit substantially increased travel of the coupler and the draft gear under buffing forces.

Another object is to provide a unit assembly including end housing, cushion and keyed follower which may be assembled outside of the car and may then be inserted as a unit in a railroad car.

This application is an improvement on co-pending application Serial No. 231,772, filed October 19, 1962, Patent 3,166,200 issued January 9, 1965 to Vernon A. Danielson and in the interest of simplification only one end of the car is illustrated.

Other objects will appear from time to time throughout the specification and claims.

The invention is illustrated more or less diagrammatically in the accompanying drawings, wherein—

FIGURE 1 is a longitudinal, horizontal part section, through an improved end housing assembly showing it in place in one end of a railroad car;

FIGURE 2 is a vertical longitudinal section through FIGURE 1;

FIGURE 3 is a section along the line 3—3 of FIGURE 1;

FIGURE 4 is a section along the line 4—4 of FIGURE 1;

FIGURE 5 is a detail plan view in part section of the end housing casting;

FIGURE 6 is a section along the line 6—6 of FIGURE 5;

FIGURE 7 is a side elevation of the end housing casting;

FIGURE 8 is an outboard end view of FIGURE 7;

FIGURE 9 is an inboard end view of FIGURE 7.

Like parts are indicated by like characters throughout the specification and drawings.

For convenience, the end housing casting will first be described, then the rigging assembly and then its installation in a railroad car.

The end housing casting, FIGURES 5 to 9 inclusive, includes a slightly tapered base 1; extending longitudinally from the base are vertical spaced straps defining side walls 2 and 3. Welded to the under sides of the straps extending from adjacent the base to the outboard end of the housing is an abrasion resistant steel floor plate 4. Extending longitudinally along the outer faces of the walls from a point just forward of the base to a point intermediate the ends of the housing are reinforcing ribs 5. At the outboard end of the housing, the walls are thickened as at 6 and 7 in prolongation of the reinforcing ribs.

The thickened portion 6 is through slotted at 8 and recessed on its outer face at 9 to receive a removable, key holding plate 10 which may be held in position by cap screws as indicated. The thickened portion 7 is slotted at 11 in opposition to and coextensive with the slot 8 but is outwardly closed. The walls 2 and 3 are through slotted at 12 and 13 between the reinforcing ribs in line with the narrower slots 8 and 11. The outer faces of the thickened wall sections 7 and 8 are in the same planes as the outer

2

faces of the reinforcing ribs and are tied together at the top of the housing by a horizontal cross wall 14.

The inner face of the base 1 is concaved at 15 to receive—as will appear more clearly in FIGURES 1 to 4 inclusive—a draft cushion 16 abutting a keyed follower 17, both of which rest upon the floor plate 4. A coupler shank 18 is slotted at 19 to receive a coupler shank key 20 which engages slots 8, 11 and 19. The floor 4 at the open end of the end housing carries a wear plate 21 associated with adjustable shims 22 in a pocket 23 engaging the shank between the key 20 and the coupler head to permit vertical adjustment of the coupler shank to compensate for wear and maintain it in proper alignment with the axis of the end housing.

10 In assembly, outside of the railroad car, the cushion 16 and the keyed follower 17 are dropped into the housing from above to rest on the floor plate 4, the coupler shank is inserted through the open end of the housing to abut on the follower. The coupler key is then inserted in

20 slots 8, 11 and 19 and the holding plate 10 is locked in place. The end housing is thus assembled, ready as a unit to be inserted and keyed into a socket for it at the end of the car.

25 Referring to FIGURES 1 to 4 inclusive, the U-shaped center sill 25 extends longitudinally of the car, being outwardly flanged as at 26 and is supported on the body bolster 27 in the usual manner. Immediately above the body bolster is a cast longitudinally apertured guide block 28.

30 In front of the bolster, an inboard supporting plate 30 is welded to the flanges 26 extending forwardly therefrom but terminating short of the outboard end of the center sill. Adjacent the outboard end of the center sill an outboard supporting plate 31 is welded to the flanges 26. These two plates together with the center sill define

35 a socket to receive the end housing.

36 Welded along the opposite outer faces of the center sill at the outboard end of the car are outwardly flanged longitudinally slotted reinforcing plates 32, the center sill walls being cut away in register with the reinforcing

40 slots to define key slots 33 in opposite walls of the center sill. In assembly, these key slots are in register with the slots 12 in the end housing and with the slot 34 in the keyed follower.

45 The housing assembly is inserted in the socket in the center sill at the end of the car and the key 35 is inserted to hold the center sill, the end housing, and the keyed follower together in working position. The mere insertion of this key is all that is necessary to hold the end housing and associated parts together in draft and buff.

50 Draft movement, that is outward movement, of the end housing and its associated parts is arrested by the draft stops 36 carried by the reinforcing plates 32 in the usual manner. The inboard ends of the slots 33 are closed by the flanges 37.

55 A push rod 38 may extend from end to end of the car, being slidably socketed at each end in the guide block 28 to abut outboard of the guide block against the end housing base and guided and aligned with the center axis of the sill as at 39. If desired, an auxiliary floating cushion such as disclosed in the co-pending application above referred to might be used in which case separate push rods will abut opposite ends of the cushion.

60 Where the outboard ends of the end housing side wall are exteriorly thickened, their outer surfaces being parallel with the outer boundaries of the reinforcing ribs, the opposed vertical inner faces of the end housing walls are tapered increasing in thickness and then decreasing in thickness in more or less hourglass form at the outer open extremity of the end housing. The resultant opposed closely spaced surfaces provide clearance for the coupler shank. The axis of the coupler key slot, being

65 approximately in line with the narrowest space between

70

the two walls, thus making it possible for the coupler shank to rotate in a horizontal plane about a vertical axis passing through the constricted area. Such angular movement of the shank being possible without exerting deleterious pressure on the end housing.

I claim:

1. In a draft gear rigging for railroad cars, an end housing having parallel vertically disposed spaced walls, an integral base closing the inboard end of the housing, a floor plate extending from the base to the outboard end of the housing, a draft cushion abutting the base, a slotted keyed follower abutting the draft cushion, both supported by the floor plate between the walls, a slotted coupler shank abutting the outboard end of the keyed follower, a coupler key in the coupler slot, one of the walls being interiorly grooved to receive one end of the coupler key and the other wall through slotted to receive the other end of the key, a removable plate masking the slot and inhibiting axial movement of the coupler key with respect to the end housing, both walls being through slotted in register with the slot in the keyed follower,

a railroad car center sill socketed to receive the end housing and means for supporting the housing slidably therein, reinforcing plates on opposite sides of the center sill, the plates and the center sill being slotted in register with the slot in the keyed follower and the housing wall, a removable key extending through all said slots to limit slidable movement of the end housing,

draft lugs carried by said plates bounding the outer ends of the slots in the center sill.

2. In a draft gear rigging for railroad cars, an end housing having parallel vertically disposed spaced walls, an integral base closing the inboard end of the housing, a floor plate extending from the base to the outboard end of the housing, a draft cushion abutting the base, a slotted keyed follower abutting the draft cushion, both supported by the floor plate between the wall, a slotted coupler shank abutting the outboard end of the keyed follower, a coupler key in the coupler slot, one of the walls being interiorly grooved to receive one end of the coupler key and the other wall through slotted to receive the other end of the key, a removable plate masking the slot and inhibiting axial movement of the coupler key with respect to the end housing, both walls being through slotted in register with the slot in the keyed follower,

a railroad car center sill socketed to receive the end housing and means for supporting the housing slidably therein, reinforcing plates on opposite sides of the center sill, the plates and the center sill being slotted in register with the slot in the keyed follower and the housing walls, a removable key extending through all said slots to limit slidable movement of the end housing,

draft lugs carried by said plates bounding the outer ends of the slots in the center sill,

a push rod abutting the end housing base extending longitudinally of the center sill and means for maintaining it in alignment with and free to move with the end housing.

3. In a draft gear rigging for railroad cars, an end housing having parallel vertically disposed spaced walls, an integral base closing the inboard end of the housing, a floor plate extending from the base to the outboard end of the housing, a draft cushion abutting the base, a slotted keyed follower abutting the draft cushion, both supported by the floor plate between the walls, a slotted coupler shank abutting the outboard end of the keyed follower, a coupler key in the coupler slot, one of the walls being interiorly grooved to receive one end of the coupler key and the other wall through slotted to receive the other end of the key, a removable plate masking the slot and inhibiting axial movement of the coupler key with respect to the end housing, both walls being through slotted in register with the slot in the keyed follower,

a railroad car center sill socketed to receive the end housing and means for supporting the housing slidably therein, reinforcing plates on opposite sides of the center sill, the plates and the center sill being slotted in register with the slot in the keyed follower and the housing walls, a removable key extending through all said slots to limit slidable movement of the end housing,

the end housing units being higher at their outboard than at their inboard ends, means depending downwardly from the center sill toward the inboard end of the housing a distance such that the clearance between the draft housing and the upper wall of the center sill is substantially the same, at both ends of the housing throughout its entire excursion.

4. An end housing casting for railroad car draft gears including a vertical base, parallel spaced vertical side walls extending from said base, the walls at the end of the housing furthest removed from the base being horizontally thickened, the walls being longitudinally through slotted between the base and the thickened wall ends, one thickened wall being interiorly longitudinally grooved in alignment with the through slot in said wall, the other thickened wall being through slotted in alignment with the slot in said wall, the slots and grooves in the thickened wall being vertically narrower than the through slots between the base and the thickened walls,

5. An end housing casting for railroad car draft gears including a vertical base, parallel spaced vertical side walls extending from said base, the walls at the end of the housing furthest removed from the base being horizontally thickened, the walls being longitudinally through slotted between the base and the thickened wall ends, one thickened wall being interiorly longitudinally grooved in alignment with the through slot in said wall, the other thickened wall being through slotted in alignment with the slot in said wall, the slots and grooves in the thickened wall being vertically narrower than the through slots between the base and the thickened walls,

reinforcing ribs extending longitudinally of the walls on both sides of the through slots, the outer faces of the thickened walls being in the same planes as the outer faces of the ribs.

6. An end housing casting for railroad car draft gears including a vertical base, parallel spaced vertical side walls extending from said base, the walls at the end of the housing furthest removed from the base being horizontally thickened, the walls being longitudinally through slotted between the base and the thickened wall ends, one thickened wall being interiorly longitudinally grooved in alignment with the through slot in said wall, the other thickened wall being through slotted in alignment with the slot in said wall, the slots and grooves in the thickened wall being vertically narrower than the through slots between the base and the thickened walls,

reinforcing ribs extending longitudinally of the walls on both sides of the through slots, the outer faces of the thickened walls being in the same planes as the outer faces of the ribs,

the horizontal distance between the thickened wall ends being a minimum adjacent the mid-point of the thickened ends and increasing gradually forwardly and rearwardly to the thickness of the reinforced wall.

7. An end housing casting for railroad car draft gears including a vertical base, parallel spaced vertical side walls extending from said base, the walls at the end of the housing furthest removed from the base being horizontally thickened, the walls being longitudinally through slotted between the base and the thickened wall ends, one thickened wall being interiorly longitudinally grooved in alignment with the through slot in said wall, the other thickened wall being through slotted in alignment with the slot in said wall, the slots and grooves in the thickened

wall being vertically narrower than the through slots between the base and the thickened walls,
the through slotted thickened wall being recessed in register with the slot and a removable cover plate in said recess making a portion of the slot.
